SUSPENDERS

Hyman Schiller, New York, N. Y.

Application December 18, 1935, Serial No. 54,983

5 Claims. (Cl. 241—12)

This invention relates to new and useful improvements in suspenders.

The invention has for an object the construction of a pair of suspenders which is characterized by non-elastic shoulder straps having their front ends bent backwards and upwards forming inner portions to which there are elastic bands attached, and the provision of rollers transversely disposed within the bent portions and associated with strips adapted to engage buttons on the front portions of the trousers. With this construction it is possible for the non-elastic shoulder straps to feed forwards or rearwards over the rollers due to the elastic bands, and so provide a resilient arrangement.

Still further the invention contemplates the provision of rings adapted to be supported by the feed rollers and an arrangement whereby the straps for engaging the buttons are attached upon said rings.

Another one of the objects of this invention is the provision of rollers with flanges arranged so that the flanges protect the edges of the shoulder straps during the operation of the device.

Still further the invention proposes a novel construction of the rollers wherein each roller is composed of superimposed shells resiliently connected with each other to produce a relatively resilient action of these parts when the shoulder straps move thereover.

Another object is the construction of a device as mentioned which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a perspective view of a pair of suspenders embodying this invention.

Fig. 2 is a fragmentary enlarged sectional view taken on the line 2—2 of Fig. 1.

Fig. 3 is an elevational view looking in the direction of the line 3—3 of Fig. 2.

Fig. 4 is a horizontal sectional view taken on the line 4—4 of Fig. 3.

Fig. 5 is a horizontal sectional view taken on the line 5—5 of Fig. 3.

Fig. 6 is an edge elevational view of a portion of a pair of suspenders which is constructed

according to a different embodiment of this invention.

Fig. 7 is a sectional view taken on the line 7—7 of Fig. 6.

Fig. 8 is a fragmentary view similar to Fig. 7 but illustrating another embodiment of the invention.

The pair of suspenders, according to this invention, comprises a pair of non-elastic shoulder straps 10 associated with a back support 11 adapted to be attached upon the back upper edge of a pair of trousers. The front ends of the shoulder straps 10 are bent at the points 10^a rearwards and upwards forming inner portions 10'.

Elastic bands 12 are attached upon the ends of the inner portions 10' and are connected with means 13 for adjustably attaching the upper ends of the bands to the shoulder straps. Rollers 14 are arranged transversely within the bent portions 10^a and are associated with rings 15 which support strips 16 formed with buttonholes 17 by which they may be engaged upon the buttons on the top front edge of a pair of trousers.

The back support 11 is composed of several parts, namely, strips 11^a, a ring 11^b, an elastic band 11^c, and a second ring 11^d. More particularly, the strips 11^a are formed with buttonholes 18 by which they may be attached upon the buttons at the rear upper edge of a pair of trousers. The inner ends of the strips 11^a are bent over the ring 11^b and are secured in this position by eyelets 19 engaging through the ends of the adjacent portions of the strip. The ring 11^b is attached upon one end of the elastic band 11^c. The attachment is accomplished by a small foundation piece 20 which extends through the ring and has its ends engaging the opposite sides of the elastic band. Stitches 21 serve to secure the foundation piece in fixed position. The ring 11^d is also held in position by a small foundation piece 20' engaging through the ring and having its ends attached on the opposite sides of the other end portion of the elastic band 11^c, by the stitches 21'. The ends of the shoulder straps 10 are secured to the ring 11^d by reason of having end portions thereof bent through the rear and held in position by eyelets 22.

The strips 16 have their upper ends engaged through the ring 15 and secured in position by eyelets 23. The ring 15 has a flat side, indicated by reference numeral 15' in Fig. 3, and the roller 14 is rotatable on this flat side. The ring 15 is formed by bending a straight strip of material into the ring shape. The ends of the strip are

bent into the roller 14 which is merely a piece of a tube.

The elastic band 12 is secured to the inner portion 10' by a small bracket 25 which is attached upon the end of the inner portion 10' and which is provided with a small metallic ring 26 through which the elastic 12 is laced. The upper end of the elastic 12 is secured by prongs 13^a to the tail end 13^b of a pivoted jaw 13^c. This pivoted jaw 10 is mounted on a slide 13^d slidably disposed on a shoulder strap. In Fig. 2 the means for adjustably attaching the elastic band on the shoulder strap, namely, means 13 is shown in the closed position. The jaw 13^c may be pivoted so that the 15 front end thereof which carries the gripping teeth 13^e is moved free from their engagement with the shoulder strap. It is then possible to slide the portion 13^d and attached parts along on the shoulder strap and thus accomplish an 20 adjustment. This controls the operative length of the suspenders.

The operation of the suspenders is very similar to a conventional pair except for the fact, that when required, the elastic 12 will stretch and 25 allow a portion of the inner portions 10' to pass over the roller 14 and move to the front. Thus, from the front there is absolutely no exposure of the elastic pieces 12 and there is the effect that the shoulder straps are resilient when in reality 30 it is merely the stretching of the elastic and the allowing of the inner portions of the shoulder strap to pass to the front to produce the desired effect and appearance.

In Figs. 6 and 7 another embodiment of the invention has been disclosed which distinguishes from the prior form merely in the provision of a roller 14' substituted for the roller 14. Each roller 14' has end flanges 14^b adapted to engage the edges of the shoulder strap. These end flanges 40 serve to protect the edges of the shoulder strap from engaging the sides of the stationary ring 15 during the drawing in and lengthening of the shoulder strap, and thus prevent fraying of the side edges.

In Fig. 8 another form of the invention is disclosed in which there is a roller 14'' consisting of an inner roller shell 14^c and an outer roller shell 14^d. A spring 14^e is interposed between these shells and has its ends attached 45 respectively to the shells so as to normally hold the shells in a neutral position. The ring 15 has its end portions 15'' flattened or of square cross section and engage in corresponding openings in the ends of the inner shell 14^c. Thus, the inner shell is held against rotation. When the shoulder straps are lengthened or shortened it is really the outer shell 14^d which will rotate, and it will 50 rotate as restrained by the resilient action of the spring 14^e. The result will be that when the suspenders are worn and in the normal condition, the shell 14^d will work itself into the neutral position. Then, when the suspenders are 55 lengthened from the normal condition, the spring will function to restrain or resist such lengthening motion in conjunction and supplementing the action of the elastic 12, thus avoiding an undue multiplicity of small lengthenings and shortenings of the shoulder straps.

While I have illustrated and described the preferred embodiments of my invention, it is to be understood that I do not limit myself to the precise constructions herein disclosed and the right is reserved to all changes and modifications 70 coming within the scope of the invention as defined in the appended claims.

Having thus described my invention, what I claim as new, and desire to secure by United States Letters Patent is:—

1. A pair of suspenders, comprising a pair of non-elastic shoulder straps, a back support attached to the rear ends of said shoulder straps, the front ends of said shoulder straps being bent backwards and upwards forming inner portions, elastic bands attached to the ends of said inner portions, means for adjustably attaching portions of said elastic bands on said shoulder straps, rollers arranged transversely within the bent portions of said shoulder straps, rings engaging through said rollers, and strips secured on said rings and formed with buttonholes for engaging buttons on 15 the front portions of trousers.

2. A pair of suspenders, comprising a pair of non-elastic shoulder straps, a back support attached to the rear ends of said shoulder straps, the front ends of said shoulder straps being bent 20 backwards and upwards forming inner portions, elastic bands attached to the ends of said inner portions, means for adjustably attaching portions of said elastic bands on said shoulder straps, rollers arranged transversely within the bent portions 25 of said shoulder straps, rings engaging through said rollers, and strips secured on said rings and formed with buttonholes for engaging buttons on the front portions of trousers, said rollers having end flanges for engaging the edges of the shoulder 30 straps.

3. A pair of suspenders, comprising a pair of non-elastic shoulder straps, a back support attached to the rear ends of said shoulder straps, the front ends of said shoulder straps being bent 35 backwards and upwards forming inner portions, elastic bands attached to the ends of said inner portions, means for adjustably attaching portions of said elastic bands on said shoulder straps, rollers arranged transversely within the bent portions 40 of said shoulder straps, rings engaging through said rollers, and strips secured on said rings and formed with buttonholes for engaging buttons on the front portions of trousers, each of said rollers comprising an inner roller shell within an 45 outer roller shell, resilient means between these shells urging them into a neutral position, and each of said rings being connected non-rotatively with the inner shell.

4. A pair of suspenders, comprising a pair of 50 non-elastic shoulder straps, a back support attached to the rear ends of said shoulder straps, the front ends of said shoulder straps being bent backwards and upwards forming inner portions, elastic bands attached to the ends of said inner 55 portions, means for adjustably attaching portions of said elastic bands on said shoulder straps, rollers arranged transversely within the bent portions of said shoulder straps, rings engaging through said rollers, and strips secured on said rings and 60 formed with buttonholes for engaging buttons on the front portions of trousers, each of said rollers comprising an inner roller shell within an outer roller shell, resilient means between these 65 shells urging them into a neutral position, and each of said rings being connected non-rotatively with the inner shell, said resilient means each comprising a spring coaxial on the inner shell and having its ends respectively attached to the inner and outer shells.

5. A pair of suspenders, comprising a pair of non-elastic shoulder straps, a back support attached to the rear ends of said shoulder straps, the front ends of said shoulder straps being bent 70 backwards and upwards forming inner portions,

elastic bands attached to the ends of said inner portions, means for adjustably attaching portions of said elastic bands on said shoulder straps, rollers arranged transversely within the bent portions 5 of said shoulder straps, rings engaging through said rollers, and strips secured on said rings and formed with buttonholes for engaging buttons on the front portions of trousers, each of said rollers comprising an inner roller shell within an outer 10 roller shell, resilient means between these shells

urging them into a neutral position, and each of said rings being connected non-rotatively with the inner shell, said resilient means each comprising a spring coaxial on the inner shell and having its ends respectively attached to the inner and outer shells, the non-rotative connection between the inner shell and the ring consisting of squared portions upon a side of the ring engaging corresponding openings in the inner shell. 5
